UNITED STATES PATENT OFFICE.

RICHARD W. UHLIG, OF RUTHERFORD, NEW JERSEY, ASSIGNOR TO UNDERWOOD TYPE-WRITER COMPANY, OF NEW YORK, N. Y., A CORPORATION OF NEW JERSEY.

TYPE-WRITING MACHINE.

1,114,315.

Specification of Letters Patent. Patented Oct. 20, 1914.

Application filed September 15, 1909. Serial No. 517,780.

To all whom it may concern:

Be it known that I, RICHARD W. UHLIG, a citizen of the United States, residing in Rutherford, in the county of Bergen and State of New Jersey, have invented certain new and useful Improvements in Type-Writing Machines, of which the following is a specification.

This invention relates to line-spacing mechanism for typewriters.

In the usual form of pawl-and-ratchet line-spacing mechanisms, the unit of line-spacing bears an aliquot relation to an entire revolution of the platen, and by means of the usual regulator, the line-spacing may be increased to two or more times that unit, but always bearing an aliquot relation thereto. It sometimes occurs that the operator desires to arrange the lines of type-writing on a form, in which the intervals between the ruled lines do not correspond with the intervals obtainable by the usual aliquot line-spacing mechanism and which subtend equal arcs of the platen circumference. In such a case, the operator feeds the platen and sheet by the usual knob fixed on the end of the platen axle, to bring each successive ruled line to the printing point. This is awkward, laborious and slow, and it frequently happens that the printed words will not be exactly on the ruled lines. To overcome this difficulty, it has been proposed to employ a friction clutch mechanism to secure even line-spacing at any interval desired; but the sheet to be written upon may have several divisions, each of which may contain ruled lines spaced a slightly greater or less distance than those in the other divisions, the intervals between the ruled lines in one division being thus aliquot relative to the intervals between the ruled lines of other divisions; and in such a case resort must be had again to the platen knob to adjust the paper.

It is one object of my invention to provide a line-spacing mechanism which will enable the operator to mechanically feed any portion of a blank form of this description through the machine so that the type-written words will fall accurately on the ruled lines, even though the intervals between the lines of one group occupy an aliquot relation to the intervals between the lines of another group.

According to the present invention, a clutch or frictional spacing mechanism is employed, the throw of which may be mechanically controlled in such a manner that any of a predetermined variety of even line spaces may be secured mechanically as desired, without the necessity of first experimenting to get just the necessary throw; and each of the several throws may bear an aliquot relation to the others. The throw of the line-spacing mechanism and platen is determined by setting a regulating lever to any of a series of positions; and a detent and rack are provided for mechanically locating the regulating lever at the desired point and holding it there; the notches or teeth in the rack having preferably an aliquot relation. I provide the platen axle with a line-space wheel to be engaged by a clutching dog, to be actuated by a line-spacing lever of usual type. A stop is adjustable to vary the throw of the clutching dog, by means of the regulating lever.

Another object of the present improvements is to relieve the adjustable line-spacing clutch mechanism from undue stress and to prevent it from being forced by the hand of the operator. This is accomplished by employing a permanent stop to arrest the clutch mechanism at the completion of the line-spacing stroke, and by so locating such stop that the line-spacing lever shall engage the usual line-space lever abutment immediately upon such arrest of the clutch mechanism, thereby relieving the clutch mechanism from undue stress caused by the pressure of the operator's hand on the line-spacing lever. At the same time, the clutch dog is caused to bite harder upon the platen-connected clutch wheel at the end of the line-spacing stroke, to prevent overthrow of the platen. The regulation of the line-spacing is effected by adjusting the stop which arrests the clutch mechanism upon its return stroke.

Other objects and advantages will hereinafter appear.

In the accompanying drawings, Figure 1 is a side view illustrating one embodiment of my invention applied to the Underwood type of front strike writing machine, the clutch mechanism being shown at rest, parts being omitted to better show the construction. Fig. 2 is a perspective view, the

clutch being shown in operation. Fig. 3 is a detail perspective view of the working parts of the invention, the clutching dog being shown in contact with the permanent stop. Fig. 4 is an edge view, partly in cross-section of the line-spacing clutch-mechanism. Fig. 5 is a detail rear view of the carrier and clutching dog.

A platen A is mounted on an axle 1 journaled in the ends 2 of a platen frame, which also carries a line-spacing spring-returned lever 3 of the Underwood type of front-strike writing machine. The line-spacing lever drives a slide 5 against the tension of a spring 6, to operate a line-spacing clutch mechanism. This mechanism includes a wheel 14 fast on the axle 1, and having a clutch flange or rim 13. A coöperating clutch member comprises a carrier 11, swinging on the axle, and having a clutching dog 10 pivoted thereto at 16, the dog having a pair of normally-disengaged jaws 12 for biting the clutch flange 13. The throw of the slide 5 is conveniently transmitted to the clutching dog by a link 7. By actuating the line-space lever 3, the slide 5 and its link 7 are driven rearwardly. The engagement of the link and pivoted clutching dog 10 operates, first, to relieve the dog from the tension of the returning spring 6 to permit a spring 19 to vibrate the dog and cause its jaws to grip the clutch flange 13, after which, the carrier 11 and clutching dog 10, together with the wheel 14 and platen, are rotated or line-spaced. Upon the release of the line-spacing lever, the spring 6 will return the slide with its link 7 to their original positions; the link operating, first, to rock the clutch dog to release it from the clutch flange 13 of the wheel 14, and then to return the dog and carrier to their inactive positions, the carrier swinging freely on the axle. The spring 6 also overcomes the tension of the clutching spring 19, and normally retains the dog in released position relative to the clutching flange 13. The throw of the clutching dog 10 and hence of the platen A is determined by an adjustable front stop 20 and a permanent rear stop 29, between which the dog swings. A link 21 connects the adjustable return stop 20 with a regulating lever 22, carrying a detent 25 receivable in any of the notches of a rack 24, two or more of such notches bearing an aliquant relation to one another, so that by throwing the adjusting lever to engage its detent with one or another of said notches, the stop 20 will be rotated together with the carrier and dog, to vary the stroke of the carrier and dog, so that the desired throw may be given the platen at the line-spacing operation. The notches of the rack 24 may be spaced to accord with the several kinds of line-space intervals on any form or any set of forms.

If the ruled lines on one portion of the form should lie for instance at .125 of an inch apart and the lines on another portion of the form (or on another form) are spaced .239 of an inch apart, it is obvious that by correspondingly locating the notches in said rack, the mechanism may be instantly adjusted for either kind of line-spacing, by merely shifting the regulating lever, with accurate results, and without the necessity of experimenting or other attention from the operator.

Obviously the number of notches on the rack may be multiplied to afford a larger number of graded adjustments of the line-spacing intervals; and they may also be located at any chosen distances, to enable the ready and accurate line-spacing of any ruled form or forms. The lever 22 is provided with a handle 23, and the detent is also equipped with a detent handle 28 for releasing the spring-pressed detent 25 from the rack. I prefer to adjust the front stop 20 to take up the throw of the clutching dog and platen at the beginning of its maximum stroke rather than at the end of such stroke.

There is enough yielding of the parts to cause the clutching dog to bite harder upon the wheel rim 13 at the end of its stroke to prevent overthrow, the stop 29 engaging the dog 10 below the pivot of the latter for this purpose. Said permanent stop 29 is placed so that the line-spacing lever 3 will strike its own abutment 4 immediately after the clutching dog engages the permanent stop. Thus the mechanism is prevented from being over strained by the pressure of the operator's hand, such strain being limited by the engagement of the line-spacing lever with its abutment.

To lengthen the life of the clutching jaws 12, I loosely seat thereon balls or rolls 15, which constantly present new faces to the flange 13 engaged thereby, when the dog is vibrated by the arm 7 connected therewith to cause the jaws to bite on the flange.

Vibration of the clutching dog may be controlled by providing the dog with a stud 17 playing in an orifice 18 in the carrier. This limits the vibration of the dog by the returning spring 6, and avoids the active engagement of the dog and flange when the line-spacing mechanism is at rest.

It will thus be seen that there is provided a line-space mechanism in which large or small line-spaces may be obtained to agree with corresponding distances between the lines of various printed forms by having an adjusting means acting to vary succeeding line-space adjustments by a predetermined irregular increment, so that certain of them have a fixed aliquant relation.

Variations may be resorted to within the scope of the invention, and portions of the improvements may be used without others.

Having thus described my invention, I claim:

1. In a typewriting machine, the combination with a revolving platen, of a line-spacing mechanism for said platen, including a clutch, means for actuating such clutch, means for limiting the extent of the line-space movement of the platen, comprising a fixed stop and an adjustable stop, and means arranged in aliquant relation for determining the adjustment of the said adjustable stop. 70
2. In a typewriting machine, the combination with a rotatable platen, of a line-spacing mechanism for said platen, including a clutch, means for actuating said clutch, means for limiting the extent of the line-space movement of the platen, comprising a fixed stop and adjustable means for determining the magnitude of the spacing movement by said line-space mechanism, such adjusting means having a plurality of stopping projections, certain next succeeding ones of which projections are at predetermined distances aliquant with respect to each other. 80
3. In a typewriting machine, the combination with a revoluble platen, and a line-space wheel connected therewith, of a line-spacing lever, an adjustable stop for limiting the line-spacing throw of the wheel and platen, a lever linked to the stop, and means for mechanically retaining the stop in different predetermined positions to regulate the extent of rotation of the platen, said retaining means including a series of stops or stations disposed at aliquant intervals. 90
4. In a typewriting machine, the combination with a rotatable platen, of a line spacing-mechanism for said platen, including a clutch, means for actuating said clutch, means for limiting the extent of the line-space movement of the platen, including notched means for varying the magnitude of the line-spacing movement by predetermined increments between the notches incommensurate with respect to each other. 95
5. In a typewriting machine, the combination with a platen and a frictional line-spacing mechanism therefor, of a shiftable stop controlling the line-spacing throw of the platen, a regulating lever connected with the stop for shifting the latter and a regulating plate associated with the lever and having an aliquant arrangement of stations to any one of which the lever may be thrown to effect a variation in the line-spacing rotation of the platen. 105
6. In a typewriting machine, the combination with a platen, of a line-spacing friction clutch mechanism therefor, including a line-spacing lever, a shiftable stop for controlling the line-spacing rotation of the platen, a lever connected with the stop for shifting the latter, and a series of positions to which the last recited lever may be thrown to permit line-spacing rotations of the platen; said stations arranged at aliquant intervals. 110
7. In a typewriting machine, the combination with a platen, of a line-spacing clutch mechanism therefor, including a line-spacing lever, a shiftable stop for controlling the line-spacing rotation of the platen, a finger-piece connected with the stop for shifting the latter, a detent carried by said finger-piece, and a rack adapted to be engaged by said detent, said rack having notches at aliquant intervals, to determine the line-spacing of the platen by corresponding aliquant movements of the platen. 120
8. In a typewriter, the combination with a frictional line-spacing mechanism, including an adjustable stop for varying the line-spacing throw of the platen, of an adjusting lever, and a link directly connecting the lever and stop, to permit the stop to be thrown to certain positions in its range of adjustment. 125
9. In a typewriter, the combination with a platen, of a frictional line-spacing mechanism therefor, including a clutch element connected with the platen, and a co-operating lever-actuated clutch member for rotating the clutch element and platen, of an adjustable return stop with which the clutch member contacts when in normal position, an adjustment connected with the return stop, and a second stop engaged by the clutch member for terminating the line-spacing stroke of the platen. 130
10. In a typewriter, the combination with a platen, a line-spacing mechanism comprising a wheel operatively connected with the platen, and having a clutching flange or rim, and a swinging carrier, of a clutching dog mounted to vibrate on the carrier, and having jaws, rolls loosely seated to turn in the respective jaws, to bite upon the flange or rim, and a line-spacing lever for actuating the dog and carrier to rotate the wheel and platen. 110
11. In a typewriter, the combination with a platen, of a line-spacing mechanism, including a clutch-element operatively connected with the platen, a swinging carrier, a clutching dog, having jaws to bite upon the clutch element, the dog mounted to vibrate on the carrier, and having a stud received in a slot in the carrier, whereby to arrest the vibration of the dog relative to the carrier, and a spacing lever for actuating the dog and carrier to rotate the platen. 115
12. In a typewriting machine, the combination with a platen, of a line-spacing mechanism including a clutch element operatively connected with the platen, a swinging carrier, a clutching dog mounted to vibrate on the carrier, and having opposing jaws to bite on opposite sides of the clutch 130

element, a slide, and a link pivotally mounted on the slide, and engaging the clutching dog, to operate the latter and the carrier and effect a rotation of the platen.

- 5 13. In a typewriter, the combination with a platen, of a clutch element operatively connected therewith, a coöperating lever-actuated clutch member for rotating the clutch element and platen, an adjustable 10 stop controlling the line-spacing throw of the clutch member and platen, a regulating lever connected with the stop, a rack having notches located at irregular intervals, and a lever-carried detent engaging the notches 15 to releasably maintain the stop in adjusted position to effect aliquant line-spacing intervals.

14. In a typewriter, the combination with a platen; of a line-spacing mechanism including a clutch element connected with the platen, a coöperating clutch member for rotating the clutch element and platen, a line-spacing lever for actuating the clutch member; a permanent stop in the path of movement of the clutch member, when actuated by the line-spacing lever, an adjustable stop with which the clutch member is engaged when at rest, and an arrest engaged by the line-spacing lever at the conclusion of its 30 line-spacing stroke for relieving the clutch member from strain.

15. In a typewriting machine, the combination with a platen, a clutch element connected therewith, a swinging clutch member 35 coöperating with the clutch element to effect a line-spacing throw of the platen, and a line-spacing lever for actuating the clutch

member, of a shiftable return stop for controlling the line-spacing throw of the clutch member, means for adjusting the shiftable 40 stop to effect aliquant line-spacing intervals, a permanent stop in the path of the clutch member for terminating the line-spacing throw of the latter, and an abutment engaged by the line-spacing lever immediately after the engagement of the clutch member with the permanent stop to prevent excessive strain on the line-spacing mechanism.

16. In a typewriter, the combination with 50 a platen, of a frictional line-spacing mechanism therefor, including a clutch element connected with the platen, and a coöperating clutch member, of a stop with which the clutch member contacts when in normal position, means to adjust said stop, and a permanent stop engaged by the clutch member for terminating the line-spacing stroke of the platen; and means adapted to prevent 55 overthrow of the platen.

17. In a typewriting machine, the combination with a revoluble platen, of a line space mechanism for said platen, and means for limiting the line-spacing movement of said mechanism definitely and quickly to 60 throws corresponding to predetermined distances between lines, the spaces between the notches having an aliquant relation to each other.

RICHARD W. UHLIG.
